UNITED STATES PATENT OFFICE.

SAMUEL WALKER, OF NEW YORK, N. Y.

MOUTHPIECE-GUARD FOR SMOKING-PIPES.

1,277,159.

Specification of Letters Patent. Patented Aug. 27, 1918.

Application filed April 4, 1917. Serial No. 159,627.

To all whom it may concern:

Be it known that I, SAMUEL WALKER, a citizen of the United States, and a resident of the city of New York, Richmond Hill, 5 borough of Queens, in the county of Queens and State of New York, have invented a new and Improved Mouthpiece-Guard for Smoking-Pipes, of which the following is a full, clear, and exact description.

10 Among the principal objects which the present invention has in view are: to enable a smoker to protect himself against contamination or infection when using a pipe; to avoid the contact of the tongue with bitter 15 portions of the mouth-piece when smoking; to furnish a smoker with single-use covers for mouth-pieces of the character mentioned; and to simplify the operation of installing in service, guards of the character men- 20 tioned.

Drawings.

Figure 1 is a perspective view of a smoking pipe having applied thereto a guard 25 constructed and arranged in accordance with the present invention;

Fig. 2 is a detail view in perspective showing an attaching ferrule employed for holding the guard in service position on the 30 mouth-piece of the pipe.

Description.

As seen in the drawings, the guard piece is preferably constructed of paper. A blank 35 or body portion 11 has at one edge a gummed section 12. As best seen in Fig. 1 of the drawings, the body section or guard piece is rolled about the mouth piece 13 of the pipe 14, and extends beyond 40 the end thereof to prevent the tongue of the smoker from touching the end of said mouth piece.

Copies of this patent may be obtained for five cents each, by addressing the "Commissioner of Patents, Washington, D. C."

When the blank is rolled on the mouth piece, the gummed edge 12 is moistened and pressed down upon the body of the wrapped 45 blank.

To hold the tube which has been formed by wrapping the body piece 11 upon the mouth piece 13 in active position, the ferrule 15 with which the stem of the pipe 14 50 is provided has a hinge tab 16 which is turned over the middle or hinge section of a spring clip 17. The spreading arms of the clip 17 are shaped to fit the curvature of said mouth piece and wrapper therefor. When 55 installing a guard in service, the clip 17 is pressed down over the adjacent end of the guard, the ends of the clip spreading to pass thereover for subsequently pressing on the sides of the guard to hold the same on the 60 mouth piece 13.

While there has herein been shown the clip 17 for preventing the inflow of air between the guard and mouth piece, it will be understood that other forms of contracting members or devices may be used, the purpose whereof is, as indicated herein, to contract the guard on the mouth piece of the pipe to prevent the flow of air therethrough.

Claim.

A guard as characterized comprising an enveloping single-service tube formed of flexible material; and means permanently attached to the mouth-piece of a pipe for holding said tube in service position, said means embodying an attachable ferrule, and a spring clip pivotally connected with said ferrule and provided with arms adapted to circumfold the mouth-piece of the pipe and 75 said tube thereon.

SAMUEL WALKER.
